[57] CLAIM

The ornamental design for a housing for a fire and smoke detector, substantially as shown.

DESCRIPTION

FIG. 1 is a plan view of a housing for a fire and smoke detector showing our new design;

FIG. 2 is a side view thereof; and

FIG. 3 is a cross-sectional elevation view of the housing taken substantially along the lines 3—3 of FIG. 1.

FIG. 2.

FIG. 3.
